UNITED STATES PATENT OFFICE.

GEORGE E. GEOGHEGAN, OF LAWRENCE, MASSACHUSETTS.

SHUTTLE-CHECKING MECHANISM FOR LOOMS.

Application filed May 15, 1926. Serial No. 109,389.

This invention relates to a shuttle checking mechanism for looms and has for its object to provide a mechanism for assisting in checking the momentum of a shuttle and bringing the latter to a final state of rest within the shuttle box, the mechanism being of such a character that it will provide an effective cushioning means for the shuttle and picker, thereby eliminating much of the wear upon the picker and picker stick, the ultimate object in view being to prolong the usefulness and life of said picker and picker stick.

Another object of the invention is to provide a mechanism for positively positioning the picker at a predetermined position of rest, so that the shuttle will always be in the same starting position when the picker is hit by the picker stick.

20 The invention consists in the shuttle checking mechanism for looms as set forth in the following specification and particularly as pointed out in the claims thereof.

Referring to the drawings:

25 Figure 1 represents a plan view of the end portion of a lay and the shuttle box at said end, a shuttle checking mechanism embodying my invention being illustrated associated therewith.

30 Fig. 2 is a front elevation of the mechanism illustrated in Fig. 1, a portion of said mechanism being broken away and illustrated in section.

Fig. 3 is a detail section taken on the line 3—3 of Figure 1.

35 Fig. 4 is a front elevation of the bumper for the picker.

Like numerals refer to like parts throughout the several views of the drawings.

40 In the drawings, 5 represents a portion of the frame of a loom, 6 the end portion of a lay, 7 the shuttle box associated with said end of said lay, 8 the top portion of a picker stick and 9 a picker, all of said parts being 45 of well-known construction and common in the art.

A shuttle 10, well known in the art, is illustrated in dotted lines in Fig. 2 resting upon the bottom plate of the shuttle box 50 and engaging the picker 9. The picker 9 is slidably mounted upon the usual spindle 11 and has a cushion 12 extending partly therearound and secured thereto by a bolt 13. The cushion 12 is constructed of any 55 suitable material, such as, leather or raw-hide, and extending around the edge of said

cushion is a band 14 of thin resilient sheet metal, said band being secured to said cushion and picker by the bolt 13. The picker 9 is secured to the picker stick 8 by a strap 15.

60 The picker 9 projects through a slot 16 in the rear wall of the shuttle box 7 and in its normal position of rest projects into an opening 17 provided within a guide 18 and engages a bumper 19 which is located at the outer end of said shuttle box.

65 The bumper 19 embodies therein a plate 20 and a cushion 21 of leather or other suitable material, said cushion resting upon the front face of said plate, and said plate and cushion are mounted to slide upon a pair of upper guide rods 22 and a pair of lower guide rods 23, the rods 22 being rigidly fastened in the framework of the shuttle box, and the guide rods 23 being secured to a 70 member 24 which is loosely mounted in the shuttle box and rests upon the bottom plate thereof. Springs 25 surround the rods 22 and yieldingly engage the plate 20 at the rear thereof, and in like manner springs 26 75 surround the rods 23 and also engage the plate 20 at the rear thereof.

80 The plate 20 has an extension 27 projecting downwardly from the lower edge thereof and through a hole 28 in the bottom plate 85 of the shuttle box, and projecting laterally from the said extension 27 are two oppositely disposed wings or projections 29 which serve to hold the bumper in position and prevent the same from having a tendency to 90 raise within the shuttle box. The extension 27 has a loose fit within the opening 28 and the latter acts as a pivot for said bumper and permits the latter to rock rearwardly and forwardly in the end of the shuttle box, and 95 at the same time slide upon the guide rods 22 and 23 against the tension of the springs 25 and 26.

100 It is desirable that when the picker 9 is in its normal position of rest that it shall always be located in the same position in order that the picker stick may always exert the same force thereon, and in order to offset any action that there may be for the bumper 19 to stick or bind upon the rods 22 and 23 a 105 mechanism is provided for positively returning said picker to a predetermined position of rest within the shuttle box. This mechanism embodies therein a push rod 30 mounted to slide in a horizontal plane in bearings 31 and 32 upon the underside of the lay and beneath the shuttle box. At its outer end 110

the rod 30 has a portion 33 bent at right angles thereto and projecting in front of the extension 27 of the bumper 19. At its inner end the push rod 30 has a downwardly projecting portion 34, and during the latter part of the beat-up movement of the lay, the portion 34 of said push rod 30 engages a cam 35 which is adjustably fastened to the frame 5 of the loom by a bolt 36, the latter projecting through a slot 37 in said cam. A guide 38 is provided for the purpose of holding the push rod 30 in position, the projection 33 of said rod resting upon said guide as said rod moves beneath said lay.

15 The general operation of the mechanism hereinbefore specifically described is as follows:—Assuming that the mechanism is duplicated at each end of the lay, as the shuttle 10 moves across said lay and enters 20 the shuttle box 7, said shuttle is retarded in its movement by the usual binder which forms no portion of this invention and which is not illustrated in the drawings. The shuttle 10 then strikes the picker 9 and forces 25 said picker and bumper 19 toward the end of the lay, said bumper sliding upon the rods 22 and 23 and compressing the springs 25 and 26 which finally bring the shuttle to a stop. Said springs immediately react to 30 force the bumper 19, picker 9 and shuttle 10 to the position illustrated in Figs. 1 and 2, which is the normal state of rest of said picker and shuttle.

If there happens to be any tendency for 35 the bumper to stick upon the rods 22 and 23 as the lay reaches its forward position in the beat-up movement, the projection 34 of the push rod 30 will engage the working face of the cam 35 and said cam will force said rod 40 30 toward the end of the lay and the portion 33 of said rod will engage the extension 27 of the bumper 19 causing the latter to rock in the opening 28 and positively force 45 said bumper, picker and shuttle to their normal positions of rest.

During the above operations excessive wear between the picker stick 8 and picker 9 is eliminated by the presence of the cushion 12 upon said picker, said cushion acting 50 to minimize the wearing action caused by the continual engagement of the picker stick with said picker.

I claim:

1. A shuttle checking mechanism for looms comprising, in combination, a lay, a shuttle box for said lay, a plurality of guide rods mounted upon said shuttle box, a bumper yieldingly mounted upon said rods, a picker adapted to engage said bumper, and means actuated by said lay to positively return said picker to a predetermined position of rest. 60

2. A shuttle checking mechanism for looms comprising, in combination, a lay, a shuttle box for said lay, a plurality of guide rods mounted upon said shuttle box, a bumper yieldingly mounted upon said rods, a picker adapted to engage said bumper, a rod adapted to operatively engage said bumper, and a cam for operating said rod, whereby said picker may be returned to a predetermined 70 position of rest.

3. A shuttle checking mechanism for looms comprising, in combination, a lay, a shuttle box for said lay, a plurality of guide rods mounted upon said shuttle box, a bumper slidably mounted upon said rods, and embodying therein a plate having an extension projecting therefrom, springs upon said rods yieldingly engaging said bumper, a picker adapted to engage said bumper, a rod mounted upon said shuttle box, and a cam for operating said rod to force the latter into engagement with said extension, whereby said picker may be returned to a predetermined 80 position of rest. 85

4. A shuttle checking mechanism for looms comprising, in combination, a lay, a shuttle box for said lay, a plurality of guide rods mounted upon said shuttle box, a bumper slidably mounted upon said rods and embodying therein a plate having an extension projecting therefrom, springs upon said rods yieldingly engaging said bumper, a picker adapted to engage said bumper, a cushion for said picker and adapted to be engaged by a picker stick, a rod slidably mounted upon said shuttle box, and a cam for operating said rod to force the latter into engagement with said extension, whereby said picker may be returned to a predetermined 95 position of rest. 100

In testimony whereof I have hereunto set my hand.

GEORGE E. GEOGHEGAN.
